DESIGN FOR A FACSIMILE TELEGRAPH MACHINE

William J. Ramhorst, New York, N. Y., and
Garvice H. Ridings, Summit, N. J., assignors
to The Western Union Telegraph Company,
New York, N. Y., a corporation of New York

Application November 25, 1939, Serial No. 88,480

Term of patent 14 years

To all whom it may concern:

Be it known that we, William J. Ramhorst and
Garvice H. Ridings, citizens of the United States,
residing at New York and Summit, respectively,
in the counties of Bronx and Union, respectively,
and States of New York and New Jersey, respec-
tively, have invented a new, original, and orna-
mental Design for a Facsimile Telegraph Ma-
chine, of which the following is a specification,
reference being had to the accompanying draw-
ing, forming part thereof.

The figure is a perspective view of a facsimile
telegraph machine, showing our new design.

The left hand side wall of the device is substan-
tially like the right hand side wall shown; the
rear wall of the device is substantially plain.

We claim:

The ornamental design for a facsimile tele-
graph machine, as shown and described.

WILLIAM J. RAMHORST.
GARVICE H. RIDINGS.
